UNITED STATES PATENT OFFICE.

WALTER C. O'KANE, OF DURHAM, NEW HAMPSHIRE.

OVEN.

Application filed February 15, 1921. Serial No. 445,092.

To all whom it may concern:

Be it known that I, WALTER C. O'KANE, a citizen of the United States, residing at Durham, in the county of Strafford and

5 State of New Hampshire, have invented a certain new and useful Improvement in Ovens, of which the following is a specification.

The object of this invention is to provide 10 an improved oven of the reflector type especially adapted for use in connection with a camp stove, such for example, as is shown in the patent issued to me March 9, 1920, No. 1,333,335.

15 The invention is embodied in the construction herein particularly shown and described, the features of novelty being finally claimed.

In the accompanying drawing forming 20 part hereof—

Figure 1 is a front elevation exhibiting the interior of the oven.

Fig. 2 is mainly a top plan view with a portion of the right hand end in section.

25 Fig. 3 is an elevation of the right hand end of the oven, it being shown as connected with the stove's rear wall which is shown in vertical section.

Fig. 4 is a transverse vertical sectional 30 view on the line IV—IV Fig. 2 looking to the left.

Fig. 5 is an end view showing how the top and bottom of the oven may be brought into a spaced relation adapted to receive the folded camp stove.

In the several views 6 designates the bottom of the oven, said bottom being formed of suitable sheet metal, and having at its rear edge a narrow wall 6^a bent up from the 40 bottom at preferably a right angle thereto.

The bottom has hinged to its ends, end walls 7 of truncated triangular forms. These end walls are of sheet metal and fold inward on the grid hereinafter described. These end 45 walls are provided with wire handles 8 hinged to fold against the walls and serve for lifting the oven when set up. Hinged at 9 to the bottom wall of the oven is a wire grid 10 adapted to be supported in operating position by means of pins 11 swiveled in

50 clips 12 secured to the inner sides of the end walls. The pins 11 are in the form of a double crank, the lower crank 11^a being bent out of line with the other so that it can be 55 easily taken with the fingers to turn the

other crank or pin into position to receive the grid. When the oven is supported on the pins the end walls are latched in erect position.

12 designates the top or upper wall of the oven, also formed of suitable sheet metal.

This wall is hinged at its rear edge to the bent up narrow wall 6^a. The front and ends of the upper wall are slightly flanged downward as seen at 12^a and 12^b to engage or 60 overhang the upper edges of the end walls as shown. When the oven is hung on the stove the top forms a cover which may be raised and lowered at will with a ring 13.

The upper corners of the end walls are provided with hooks 14, as shown in Fig. 4, to hook over the upper edge of the rear wall 65

15 of the camp stove as shown in Fig. 3. The narrow rear wall 6^a of the bottom of the oven is provided with a leg 16 hinged to 70

turn up edgewise next to said wall. Said end wall 6^a is provided with a guard 17 within which the leg turns to aid in preventing pronounced flexing of the leg. The top 75

and bottom walls of the oven can be made 80 bright on their inner surfaces so as to reflect heat in the general direction of the grid and articles placed thereon for baking or roasting.

An important feature of the invention is 85 that the oven can be opened for the examination and change of the contents by merely raising the top and without detaching the oven from the stove. Another important

feature of the invention as thus embodied is 90 that every part of it is connected with the others so that no part can be lost.

The camp stove of my former patent referred to is capable of compact folding, and the oven herein described is also capable of 95 being folded as suggested in Fig. 5, but by reason of the rear wall 6^a the top and bottom walls may be so positioned as shown in Fig. 5 as to receive between them the folded stove. When the two articles are so nested 100 they occupy very little more space than either one.

The forms of the parts can be varied somewhat without departing from the gist 105 of the invention as claimed.

What I claim is:

1. In an oven of the kind described, the combination of a bottom wall and a top wall hinged to the rear of the bottom wall, end 110 walls hinged to the ends of the bottom wall

and hooks fixed at the forward upper corners of the end walls to engage the oven-heating wall of a stove.

2. In an oven of the kind described, the
5 combination of a bottom wall and a top wall
hinged thereto, end walls hinged to the ends
of the bottom wall, a grid hinged to the bot-
tom wall, and means for engaging said grid
10 with said end walls to hold them in erect
position and hooks fixed to the forward up-
per corners of the end walls to engage the
oven-heating wall of a stove.

3. In an oven of the kind described, the
combination of a bottom wall, end walls
hinged to the ends of said bottom wall, a 15
grid hinged to the bottom wall, a top wall
hinged to the rear of the bottom wall and
means on the end walls for engaging the
grid with those walls when the latter are
erected to the position of use, said means 20
consisting of swiveled pins having disaligned
hooks projecting therefrom.

WALTER C. O'KANE.
